PAGE 2

FIG. 2.

FIG. 3.

Figure 1 is a perspective view of a combination storing and dispensing display holder for coiled metal tape or the like showing my new design;

I claim:

The ornamental design for a combination storing and dispensing display holder for coiled metal tape or the like, substantially as shown.
